CONTROLLED TEMPERATURE GRADIENT VAPOR-GENERATOR

Russell S. Miksch, Redwood City, and Robert E. Corridan, Los Altos, Calif., assignors to American Radiator & Standard Sanitary Corporation, New York, N.Y., a corporation of Delaware

Filed Sept. 5, 1961, Ser. No. 136,076
6 Claims. (Cl. 122—4)

This invention relates to and in general has for its object the provision of a vapor-generator for supplying vapor to any desired equipment such as, for example, the jet of an attitude deviation correction motor of a space vehicle.

It is essential that generators for this purpose be compact, of low weight, and mechanically simple.

More specifically, one of the objects of this invention is the provision of a generator of the character above described, independent of the existence or action of gravity, and including: a reservoir containing a liquid and its vapor in two-phase equilibrium with each other; an evaporator-superheater connected to the reservoir through a restricted connector and provided with a valved outlet; and means for maintaining the temperatures in the reservoir and the evaporator-superheater such that the temperature in the latter is higher than that in the reservoir and that pressures in the two are substantially equal to each other when the valved outlet is closed and are higher than downstream pressure when the valve is open. In such a system, dry vapor will always be available at the valved outlet at a pressure greater than the ambient pressure, and when the outlet is opened in response to a demand signal vapor will flow through the outlet under the influence of the existing differential pressure. The flow of vapor out of the system reduces the pressure within the superheater, this reduces the pressure and increases the vapor volume within the generator, and consequently produces a flow of vapor and/or liquid through the reservoir outlet into the superheater, and a flow of vapor through the valved outlet is maintained in response to the demand signal.

The invention possesses other advantageous features, some of which, with the foregoing, will be set forth at length in the following description where those forms of the invention which have been selected for illustration in the drawings accompanying and forming a part of the present specifications are outlined in full. In said drawings, several forms of the invention are shown, but it is to be understood that it is not limited to such forms, since the invention as set forth in the claims may be embodied in other forms.

Referring to the drawings:

FIG. 1 is a schematic drawing of a vapor-generator of the character above described embodying the objects of our invention.

FIG. 2 is a typical pressure-enthalpy chart indicating the manner in which the generator illustrated in FIG. 1 operates to generate vapor at a constant pressure.

FIG. 3 is a schematic drawing of a modification of the generator illustrated in FIG. 1.

FIG. 4 is a schematic drawing illustrating an alternative way of operating the generator shown in FIG. 3.

More specifically, and as illustrated in FIG. 1, the objects of our invention have been embodied in a system including a closed reservoir generally designated by the reference numeral 1 communicating through a restricted connector 2 with an evaporator-superheater generally designated by the reference numeral 3. Preferably, this entire system is thermally shielded as at 4. Although certain limitations are placed on the size of connector

2

2, it need not be of capillary dimensions, for, as will presently more fully appear, the action of our generator does not depend upon capillary forces to produce fluid movement.

5 Located within the reservoir is a heat-generator here illustrated as an electrical heater 5 connected through external leads 6 and 7 with a temperature-controller 8.

Mounted within the evaporator-superheater 3 is a heat-generator here illustrated as an electric heater 9 communicating through external leads 11 and 12 with the temperature-controller 8. The temperature-controller 8 senses the temperature in the reservoir 1 through a line 10 and the temperature in the evaporator-superheater 3 through a line 10a. Although not shown, there is associated with the temperature-controller 8, the reservoir 1, and the evaporator-superheater 3, means for sensing the temperatures in the two latter components so as to enable the temperature-controller 8 to maintain the temperature in the evaporator-superheater 3 at a higher value than the temperature within the reservoir 1.

20 Disposed within the evaporator-superheater 3 is a maze 13 forming a tortuous path through which any fluid in the superheater is constrained to travel thereby to effect a better heat exchange between such fluid and the heater 9.

25 Communicating with the superheater 3 is an outlet 14 which, if desired, may be connected, by way of example, with the intake of the jet orifice of attitude deviation correction motor not shown. Connected in the outlet 14 is a motor-actuated valve 15 which, again for purposes of illustration, may be under the control of an attitude-sensor (not shown) through a line 16.

30 Contained within the reservoir 1 is a body 17 of fluid which, as indicated by the line 18, may be partially in its liquid phase and partially in its vapor phase, these phases being in equilibrium with each other.

35 Although, as previously stated, the restricted connector 2 need not be of capillary dimensions, its dimensions should be such that the rate of flow of fluid therethrough from the reservoir 1 to the evaporator-superheater 3 will not exceed the rate at which the latter is able to evaporate the liquid content of fluid entering it.

40 Also, as previously indicated, the temperature-controller 8 is arranged to maintain the temperature within the evaporator-superheater 3 at a higher value than the temperature within the reservoir 1 to just insure that all of the fluid entering the former will be converted into its vapor or gaseous phase. However, since the reservoir 1 and the evaporator-superheater 3 are continuously 45 interconnected by passageway 2, the pressure within the evaporator-superheater 3 is nevertheless equal to the pressure within the reservoir 1, provided the valve 15 remains closed.

45 Now referring to FIG. 2, wherein the points A and B represent the conditions of the fluid in reservoir 1 and at the outlet 14 with the valve 15 closed. Liquid at A is at its saturation temperature and pressure, and the vapor at the outlet 14 is at substantially the same pressure, although at a higher temperature. The characteristics of two-phase liquid-vapor systems are such that, at any given pressure, liquid can exist in equilibrium with its own vapor at only one temperature. The imposition 50 of a higher temperature in the evaporator-superheater 3 therefore assures that only dry vapor will be present therein.

55 When the valve 15 opens in response to a demand signal and vapor is discharged therethrough, the pressure in the system will tend to drop in accordance with Boyle's law ($PV=K$ where the temperature remains constant) and consequently additional liquid in the reservoir 1 will 60 be converted to vapor. Since the specific volume of a

vapor is much greater than that of its liquid, the resulting additional evaporation in the reservoir 1 will increase the total volume of fluid therein, some of which will flow through the connector 2 into the evaporator-superheater 3 and thus equalize the internal pressures within the system. All this is indicated in FIG. 2 by the horizontal line A-B, it of course being here assumed that the temperature-controller 8 is arranged to maintain the required temperature within the reservoir 1 relative to the temperature within the superheater 3 or, in other words, to replace the heat carried from the reservoir either as sensible heat or latent heat of the fluid entering the superheater. Either liquid or vapor, or a mixture thereof, may be discharged from the reservoir with equivalent results, since the condition of the fluid leaving the outlet 14 will be vapor in either case.

A variety of liquids can be used for this purpose, such as for example water, propane and ammonia. Also, chemical heaters can be used instead of electrical heaters.

Through proper design of the fluid flow and thermal characteristics of the system, and without relative movements of internal parts, the generator system above described may be operated without regard to the presence or direction of gravitational forces to prevent the escape of liquid from the generator, while supplying dry vapor for any requirement.

Now referring to the modification illustrated in FIG. 3. With one exception, this modification is identical with the modification shown in FIG. 1, and consequently its component parts have been referred to by the primes of reference numerals used in FIG. 1.

The single exception referred to is that housed in the reservoir 1' is a Sylphon or bellows 18 sealed to the inner wall 19 of the reservoir and forming a chamber 21 communicating with the restricted passageway 2'. Surrounding the reservoir 1' is a heating element 22 connected by leads 23 and 24 with the temperature-controller 8'. Defined by the reservoir 1 and the Sylphon 18 is a pressurizing chamber 25 containing a body 26 of ammonia.

Example 1.—Self-pressurized propane vapor generator

Now referring back to FIG. 1: Assume the propellant reservoir to be maintained at a temperature of 105° F. and the evaporator-superheater to be kept at 120° F. Then with a propellant charge whose liquid volume is less than the volume of the reservoir 1, attainment of thermal equilibrium conditions will result in all liquid residing in the reservoir 1, and the pressure in the reservoir will be the saturation pressure of propane at 105° F. or 200 p.s.i.a. Because the reservoir 1 and the evaporator-superheater 3 are interconnected, pressure in the latter will also be 200 p.s.i.a., but since its temperature is higher than the saturation temperature at the prevailing pressure, the vapor in the evaporator-superheater will be superheated. Operation of the valve 15 to connect the evaporator-superheater 3 to a region of lower pressure will result in flow of vapor from the evaporator-superheater, with consequent lowering of pressure therein. Pressure in the reservoir 1 will also tend to decrease, and additional liquid will be vaporized in the reservoir to restore equilibrium. A volume of fluid (either vapor or liquid or both) equal to the volume of vapor thus produced will flow toward the evaporator-superheater 3 to become dry superheated vapor at 120° F., from where it will proceed through the evaporator-superheater to the outlet. These events will continue as long as the valve is open or until the reservoir 1 is emptied.

Example 2.—Ammonia-pressurized propane vapor-generator

Now assume that the ammonia 26 is in two-phase equilibrium and that the expandible chamber contains propane, that the chamber 25 is maintained at 105° F. and that the evaporator-superheater is maintained at 120° F. The system pressure will now be 229 p.s.i.a., which

is the saturation pressure of ammonia at 105° F. The fluid in the chamber 21 will be entirely liquid, since the prevailing pressure of 229 p.s.i.a. is greater than the saturation pressure of the propane at 105° F. (200 p.s.i.a.). Upon opening the valve 15' for vapor discharge, the events taking place in this system will parallel those taking place in Example 1, except that all fluid leaving the chamber 21 will be liquid.

Example 3.—Water-vapor-pressurized water vapor-generator

This example is illustrated in FIG. 4 wherein it will be seen that, in so far as structure is concerned, it is identical with that illustrated in FIG. 3. For that reason the corresponding elements have been indicated by identical reference numerals. However, here the pressure chamber 25 contains a body 26' of water and water vapor, and water is also used as the propellant in the expandible chamber 21. Heating of the chambers 21 and 25 is so arranged that when the system is not in thermal equilibrium, that is, 25 is hotter than 21, heat may pass from 25 to 21. Now assume that 21 and 25 are maintained at 265° F. and that 3' is maintained to 280° F. The system equilibrium pressure will be 38½ p.s.i.a. (saturation vapor pressure of water at 265° F.), which will allow thrust nozzles connected to 14' to operate supersonically under normal atmospheric conditions. While the control valve 15' is closed, 21 may contain both liquid and vapor as in the case of Example 1. When the valve 15' is open and vapor is discharged, fluid moving from 21 to 3' may initially be liquid or vapor or both, as in the case of Example 1. Continuous operation will at some time result in a drop in temperature in 21 below the temperature in 25. At this time, vapor in 21 will be transformed to liquid, since it will be subjected to the pressure of 25, greater than its own saturation pressure. Therefore, during this continued operation, conditions in this system will correspond directly to the conditions described with reference to Example 2.

The principal advantage of the system shown in FIGS. 3 and 4 over and above advantages of the system shown in FIG. 1 is that they have greater stability of operation during continuous vapor demand, since the site of vaporization of the liquid is more clearly established. This is particularly true with respect to the second example. Temperature controls and heating device are less subject to random cycling, and reliability is therefore higher.

We claim:

1. A vapor-generator for space vehicles comprising: a first sealed chamber provided with a vapor plenum, means fluidly communicating to the interior of said first chamber consisting of a single connector connected thereto, a second sealed chamber, said connector being permanently restricted and connected to said second chamber, each of said chambers containing a quantity of chemically identical fluids, said second chamber being provided with a valved outlet; means for maintaining the fluid content of said second chamber at a temperature higher than the temperature of the fluid content of said first chamber and at a temperature above the boiling point of the fluid content of said second chamber at the existing equilibrium pressure of said first and second chambers; and means operable upon the opening of said outlet for maintaining the fluid in said first chamber essentially at said equilibrium temperature and pressure.

2. A vapor-generator for space vehicles comprising: a first sealed chamber provided with a vapor plenum, means fluidly communicating to the interior of said first chamber consisting of a single connector connected thereto, a second sealed chamber, said connector being permanently restricted and connected to said second chamber, each of said chambers containing a quantity of chemically identical fluids, said second chamber being provided with a valved outlet; means for maintaining the fluid content of said second chamber at a temperature higher than the

temperatures of the fluid content of said first chamber and at a temperature above the boiling point of the fluid content of said second chamber at the existing equilibrium pressure of said first and second chambers; and means operable upon the opening of said outlet to replenish the heat content of the liquid in said first chamber so as to maintain the pressure of the vapor discharged from said outlet at a constant pressure.

3. A generator of the character set forth in claim 1 wherein the fluid flow capacity of said restricted connector is such that under operating conditions fluid will flow therethrough from said first chamber to said second chamber at a rate not greater than the liquid content thereof can be evaporated in said second chamber when said outlet is open.

4. A vapor-generator of the character set forth in claim 1 wherein said first chamber is in the form of an expansible chamber, and wherein means is provided for varying the volume of said expansible chamber.

5. A vapor-generator of the character set forth in

claim 4 wherein said expansible chamber is surrounded by a pressure chamber and wherein means is provided for varying the pressure within said pressure chamber.

6. A vapor-generator of the character set forth in claim 1 including a temperature controller operating in response to variations in the temperatures within said first and second chambers for maintaining said temperatures at substantially predetermined values.
